WILLIAM B. CLAFLIN, JR., OF NEW CANAAN, CONNECTICUT, ASSIGNOR TO CLAFLIN PRODUCTS INCORPORATED, OF NEW CANAAN, CONNECTICUT, A CORPORATION OF CONNECTICUT

TROUSER HANGER

Application filed January 12, 1932. Serial No. 586,150.

My invention relates to garment hangers and more particularly to garment hangers of the swinging type adapted to accommodate several garments, any one of which may be 5 removed from the hanger without in any way interfering with the other garments.

My improved garment hanger is especially suitable for use as a hanger for several pairs of trousers, although it is to be understood 10 that it may also be used for the purpose of hanging other garments. One of the objects of the invention is to provide a garment hanger of the swinging type and of such compact construction that it occupies a minimum 15 of space. A further object is to provide a garment hanger of this character so constructed that several individual garment holders are provided, any one of which may be used without the necessity for handling 20 any other garments carried by the other holders. I prefer to arrange the several individual holders in such a manner that they can all be swung into close proximity to each other and locked in this position so that the 25 several holders and the garments carried thereby will occupy very little space. A further object of my invention is to provide a swinging garment hanger comprising several holders all of which are mounted so as 30 to swing in a common horizontal plane. The garment hanger is intended to be mounted permanently on a wall or other supporting surface, and where all of the individual holders are mounted so as to swing in a common 35 horizontal plane, the garment hanger can be mounted at an elevation that is convenient for the person using the same and all of the individual holders are readily available.

40 In general my invention comprises a support which may be provided with a base portion adapted to be affixed to any stationary surface such as a wall or a door casing or molding. The support is provided with several vertical rods preferably arranged parallel to each other in a common plane extending outwardly at an angle from the base portion of the support. Each of the rods may carry a garment holder and where the rods are arranged in vertical position parallel to each

other, the several holders may be swung about in a common horizontal plane. Each individual holder is preferably formed of a single piece of resilient material such as heavy wire or metal rod stock. The wire 55 holder is of such configuration as to provide at least one pair of cooperating arms extending out away from the vertical rod supporting the holder and the wire may be provided with loop portions encircling the upper and 60 lower ends of the supporting rod, thus providing a hinged connection between each holder and the hanger's support.

The garment hanger support may be provided with a projection forming an abutment 65 adapted to engage one of the individual garment holders to hold it in a predetermined angular position and the arrangement of the several parts may be such that this projection serves to lock all of the swinging holders 70 in close proximity to each other.

While I prefer to employ heavy wire or rod stock in making the swinging holders, it is to be understood that some features of my invention may be employed to advantage where 75 the swinging holders are made out of other material. For example, they may be made out of flat, sheet material stamped and bent into a form to provide a pair of arms for engaging a garment. It is also feasible to employ flat spring stock for this purpose and to attach to the spring member fibrous material, 80 ply-wood or the like, to form a clamp for engaging the garment. Where heavy wire or rod stock is employed in making the swinging 85 holders I prefer to make each holder out of a single piece of wire, but it is to be understood that if desired a number of pieces can be employed, the several pieces being secured 90 together.

The various objects and advantages of my invention will be more apparent upon considering the following detailed description which is to be considered in conjunction with the accompanying drawing in which

95 Fig. 1 is a top plan view of one embodiment of my hanger;

Fig. 2 is a front elevation of the hanger illustrated in Fig. 1;

Fig. 3 is a transverse section view taken 100

on line 3—3 of Fig. 2 showing one of the garment holders supporting a pair of trousers;

Fig. 4 is a transverse section view taken on line 4—4 of Fig. 2 showing the construction of the upper end of one of the swinging garment holders; and

Fig. 5 is a transverse section view taken on line 5—5 of Fig. 2 showing the construction of the lower portion of one of the swinging garment holders.

The embodiment of my invention illustrated in the accompanying drawing comprises a support 1 having a base portion 2 adapted to be secured to any desired surface such as the wooden molding strip 3, by means of screws 4. The support 1 may be regarded as a wall bracket including the base portion 2 and a pair of supporting arms 5 and 6 extending away from the base portion at an acute angle thereto. The extremities of these arms may be supported by braces, one of which is shown at 7 in Fig. 1. The entire support or bracket may consist of a single metal stamping, or it may consist of several parts fastened together, as may be desired.

A plurality of rods 8 are mounted between the arms 5 and 6. For purposes of illustration I have shown four rods mounted between the arms 5 and 6 but it will be understood that any desired number of rods may be employed. A swinging garment holder is mounted on each of the rods 8, the several garment holders being designated by the reference numeral 9.

In the particular embodiment of the invention illustrated in the accompanying drawing, each swinging garment holder 9 consists of a single piece of heavy wire or rod stock bent to provide a pair of loops for engaging the upper and lower ends of the supporting rod 8 associated therewith and so as to provide a plurality of cooperating arms disposed in substantially parallel relation with each other and adapted to engage a garment. Each wire garment holder 9 is provided with a loop 10 loosely engaging the upper end of the supporting rod 8 and the ends of the wire are welded or otherwise secured together, as shown at 11 in Fig. 5, to form a second loop 12 encircling the lower end of the rod 8. The portions of the wire between the loops 10 and 12 are bent so as to provide a pair of arms 13 and 14 extending outward away from the upper end of the supporting rod 8. The wire is then bent upward and rearwardly to form a second pair of arms 15 and 16. The rear extremities of these arms 15 and 16 are bent downwardly, as illustrated at 17 in Fig. 2, and terminate in the ends joined together at 11 to form a loop 12 engaging the lower end of the supporting rod 8.

The curved outer extremities of each swinging garment holder are preferably

spread apart somewhat to facilitate the insertion of one end of a garment between the gripping arms of the holder. This is best illustrated in Fig. 1, which shows the extremities of the holders twisted to such an extent that the upper pair of arms 15 and 16 are separated from each other to a greater extent than the lower pair of arms 13 and 14. In using the garment hanger it is merely necessary to slip an extremity of the garment between the opposed pairs of arms and these arms will hold the garment in a suspended position. Where the hanger is used as a hanger for trousers, the garment may be inserted between the holder arms in the manner illustrated in Fig. 3. In this figure the trouser cuffs 18 are supported between the upper arms 15 and 16 and the lower arms 13 and 14 engage the trouser legs at the edge of the cuffs.

It will be understood that each of the individual swinging garment holders may be swung about on its vertical rod support in the manner illustrated in dotted lines in Fig. 1. After several garments have been suspended from the holders, the several holders may be folded back against the wall where they are disposed in close proximity with each other and occupy a minimum of space. The holders may be locked in this position by a locking projection or lug 19 carried by the hanger bracket or support 1 and forming an abutment engaging the edge of the outermost garment holder, as shown at 20. The loop portions of the garment holders engaging the vertical supporting rods 8 may be maintained in proper spaced relation to each other by means of spacer sleeves 21. A spring 22 may engage the loop 10 of the outermost garment holder to hold this garment holder in engagement with the locking projection 19 and it will be understood that when it is desired to remove a garment from the hanger the outermost garment holder may be lifted against the force of the spring 22 until this garment holder disengages the locking projection 19, whereupon the garment holder may be swung back, as illustrated in dotted lines in Fig. 1. This releases all the other garment holders and they may be swung to any convenient position to facilitate the removal of a garment from any one of the holders.

If desired, the portions of the arms 13, 14, 15 and 16 adjacent to the loops 10 and 12 may be welded together as illustrated at 23 and 24 in Figs. 4 and 5. By fastening the arms together at this point the arms are always maintained in proper relation to each other and the loop portions 10 and 12 are prevented from spreading apart.

In the preferred embodiment of my invention illustrated in the accompanying drawing, each individual garment holder consists of a single piece of heavy wire or

the like having its ends welded or otherwise secured together. It is convenient to have this joint disposed in the position illustrated in Fig. 5, for there is no strain on the holder at this point. The corresponding portion of the upper loop 10 of each garment holder is under tension due to the weight of the garment carried by the holder, but the configuration of the holder is such that the lower loop 12 is not under tension.

It is to be understood that my invention is not limited to the particular embodiments thereof illustrated and described but includes such modifications thereof as fall within the scope of the appended claims. It is also to be understood that my invention is useful with garments or wearing apparel in general, for example, the hanger may be used as a necktie holder, in which event several ties may be suspended from each of the swinging arms.

I claim:

1. A garment hanger comprising a support, a plurality of garment holders mounted on said support to swing in a common plane, means associated with one of said holders and with said support for locking all of said holders against swinging in said common plane and in at least partial contact with each other, said locking means comprising a projection carried by said support for engaging one of said holders, and resilient means for engaging the last mentioned holder and maintaining it in engagement with said projection.

2. A garment hanger comprising a support, a rod carried by said support, and a garment holder loosely mounted on said rod and consisting of a single continuous elongated piece of material having a loop portion intermediate its ends encircling one end of said rod and having its ends secured together to form a loop encircling the other end of said rod, the remaining portions of the holder forming a pair of arms for engaging a garment.

3. A garment hanger comprising a support, a vertical rod carried by said support, and a garment holder loosely mounted on said rod and consisting of a single piece of wire bent to form a pair of loops for engaging the upper and lower ends of the said rod, the portions of the wire between the said loops being disposed in such a manner that the wire extends outwardly away from the upper end of the said rod then upwardly and rearwardly in a direction towards the said rod and then downward toward the lower end of said rod whereby a pair of arms are formed for engaging a garment.

4. A garment hanger comprising a support, a vertical rod carried by said support and a garment holder comprising a piece of wire, means for pivotally attaching the wire to the upper and lower ends of the rod, the

portions of the wire between said attaching means being disposed in such a manner that the wire extends outwardly away from the upper end of said rod, then upwardly and rearwardly in a direction toward said rod and then downwardly toward the lower end of said rod, whereby a pair of arms are formed for engaging a garment.

In testimony whereof I affix my signature.
